UNITED STATES PATENT OFFICE.

GIDEON SUNDBACK, OF MEADVILLE, PENNSYLVANIA, ASSIGNOR TO HOOKLESS
FASTENER COMPANY, A CORPORATION OF PENNSYLVANIA.

FASTENER.

Application filed January 8, 1923. Serial No. 611,211.

To all whom it may concern:

Be it known that I, GIDEON SUNDBACK, a subject of the King of Sweden, and resident of Meadville, in the county of Crawford and State of Pennsylvania, have invented certain new and useful Improvements in Fasteners, of which the following is a specification.

This invention relates to fasteners of the type described in my Patent No. 1,243,458, October 16, 1917, which shows a plurality of interlocking members disposed along the edges of stringers on opposite sides of a slit where the interlocking members are controlled by a slidable operating device. An object of this invention is to provide increased flexibility and reliability, reduced cost of production, and longer life of the fastener.

According to this invention, a clearance is provided between the projection of one interlocking member and the walls of the recess in its cooperating member so located relatively to the stringers and the heads and recesses as to adapt this fastener for use with washable articles such as overalls, children's clothing, etc., where difficulty has been encountered due to shrinkage of the tape stringers, or the fabric to which attached. This clearance results from a different contour of the sockets and projections shown in said patent and enables quite wide variations in stringer length and member spacing to exist without causing the members to jam, or to become so loose as not to stay interlocked. Also, where the members tend to jam, excessive wear is caused on the slider, or even distortion sufficient to render a new one necessary. Since the projections and cooperating sockets are not so nearly identical in fit, as in said patent, the dies and punches used in making the members need not be of such high precision, and may be used for a longer time when worn from their original contour because of the greater clearances permitted by this invention, thus cheapening the tool and labor cost of production.

Referring to the drawings:

Fig. 1 is an enlarged view of the improved fastener, mounted on cords 6 sewed to stringers 26.

Fig. 2 is a section on the line 2a—2a of Fig. 1.

Fig. 3 illustrates the die and punch used in forming the projection and recess in each interlocking member.

Figure 1 shows a plurality of interlocking members 7 secured to the stringers 26 along opposite sides of an opening and adapted to be controlled by the slidable operating device 8 in a similar manner to that described in my Patent No. 1,243,458, October 16, 1917. Each interlocking member 7 is provided with a projection 3 on one side thereof and an aligned recess 2 on the opposite side for cooperation with the projection of the adjacent interlocking member. These projections and recesses are transversely elongated as shown in the previous patent referred to, and the operation of these members is similar to that described in the patent. So also each stringer 26 may be provided with an end member 10 for limiting the movement of the slider 8 in closing the slit and the opposite ends of the stringers may be permanently secured by a member 9 as is also described in that patent.

An essential distinction resides in the provision of clearance between adjacent interlocking members. To accomplish this result each recess is made considerably larger than its cooperating projection as shown in the drawing, and the adjacent members 7 are separated so as to be normally spaced apart when interlocked. The provision of longitudinal or axial clearance 12 between adjacent interlocking members enables this fastener to be applied to washable goods which are likely to shrink. When the interlocking members closely fit within one another, as indicated in the prior patent referred to, shrinkage of the material results in bringing the interlocking members so close together as to be incapable of properly engaging, or if unusual means are taken to move the

slider, the interlocking members will be moved out of their positions on the stringers, which invariably makes the fastener useless for future service. The amount of separation between adjacent interlocking members must bear a relation to the height of the projection and must be less than one-half the height of such projection. In other words, the distance from the top 15 of a projection to the bottom 16 of its cooperating socket, when in normal position, must be greater than the separation of the connecting members, so that if one of the interlocking members be moved longitudinally 20 into contact with the adjacent member on one side, the adjacent interlocking member on the opposite side must still be in cooperation in order to prevent the fastener from becoming open. Both the sockets and projections in this invention are made tapered in order to better provide guiding surfaces as the slider brings the members into interlocked position, and as described in Patent No. 1,243,458. With tapered surfaces for the 25 recesses and projections a certain amount of lateral clearance is necessary as shown in Figure 1 in order to allow the desired longitudinal movement with shrinkage and stretching of the washable goods. In Fig. 2 it will be observed the recesses and projections are transversely elongated, and with 30 slightly less clearance between the members in the transverse direction shown in this figure than is the case in the plan view 35 shown in Fig. 1. In Fig. 1 it will be noted the outer surface 19 of each projection is substantially continuous with the outer surface 20 of the interlocking member, while in Fig. 2 the transverse section shows that in 40 this direction the surface 17 of the projection is not continuous but forms an angle with the surface 18 of the interlocking member. The clearance shown in Fig. 2 must not be too large or the fastener might be 45 opened by moving one of the interlocking members to the right or left of its position shown in this figure, when these members might become unlocked if the clearance is not within the permissible limits. Any 50 form of stringers 26 may be used, either the kind described in my Patent No. 1,243,458, or that of my Patent No. 1,322,650 of November 25, 1919.

When the interior surface 1 of the slider 55 8 became worn beyond a small amount, the interlocking members of the previous patent would not necessarily be brought into engagement and properly interlocked. This wear takes place in all fasteners and the 60 length of serviceability in this respect varies with the relation between the width of the channel in the slider, the width of the fastener, and the clearance between projections and recesses. With the lateral clearance 65 indicated between projections and recesses

the fastener will continue serviceable until such wear results that the outside edge 13 of the recess will not move down over the inside edge 14 of a projection.

Fig. 3 shows how the punch 5 operates 70 on the connecting member 7 in the die 4 to form the recess and projection in one operation. Since the recess is larger than the projection the same care need not be exercised in having the recess and projection of precisely the right size, and, therefore, the punch 5 and the die 4 may be used for a longer time after they have become worn more than was previously permissible without the clearance. Prolonged use of the 80 dies and punches obviously results in a cheapened cost of production. As shown in the drawing the sides of the recess and projection are tapered and form an angle of about 33° with the vertical. Or, more precisely, the surfaces 17, 19 and 20 are inclined at substantially 33° with the vertical, while the surface 21 is somewhat steeper, being at an angle of about 25°, and the surface 18 is more steep, being at an angle of about 12° 85 with the vertical. It will be understood that these surfaces are rounded and that no edge or sharp line of demarkation exists between the surfaces 17, 19 and 21. Being rounded the intermediate surfaces gradually change 90 their inclination.

In addition to the foregoing needs for lateral clearance, such is especially necessary when the interlocking members are of varying widths, as otherwise these members could not be readily engaged and disengaged. The variations in width of the interlocking members may result from a number of causes, such as the wearing of rolls 100 in making the wire in the formation of these interlocking members, the wearing of the cutting die and knives in the slicing machine for making these members, the adjustments and irregularities in the forming machines, and the setting of the tools which 105 form the projections and recesses in the interlocking members. Also the sliders may vary in internal width at the time of production as well as due to wear.

Among the advantages of this invention 110 may be enumerated the greater flexibility of the fastening in all directions when provided with the clearance described without lessening the holding power. Greater wear 115 being possible on the internal surface of the slider makes for longer life and ability of this fastener to stand up under more prolonged usage. The field of use of this invention is enlarged because applicable to wash goods wherein shrinkage may occur. The reduced cost of production through the necessity of grinding the punches and dies 120 less frequently is another advantage. This fastener may be used on curved or straight 125 slits, with any type slider, and locking 130

means, and with or without protective flaps, in short, any place where the previous fastener of Patent 1,243,458 may be used.

I claim:

5. 1. A plurality of interlocking members for an opening, which are adapted to be controlled by a slider, each of said members being provided with a projection on one side and a recess on the opposite side in axial 10 alignment with said projection, the recess being enough larger than the projection to permit a lateral movement between the interlocked members.

15. 2. In a fastener, an interlocking member having a rounded recess on one side, and a rounded projection on the opposite side continuous with the outer edge of said member, said recess being larger than said projection to provide both lateral and transverse clearance, the lateral clearance being greater than 20 the transverse clearance.

25. 3. A plurality of interlocking members for an opening controlled by a slider, each member having a tapered projection on one side and a larger tapered recess on the opposite side, said members being arranged along the opposite edges of said opening to permit shrinkage of the material containing said opening and permit said members to 30 be moved together longitudinally while not interlocked without interfering with the ability of said members to be controlled by the slider.

35. 4. A fastening means for the opposite edges of a slit material adapted to be progressively controlled by a slider and comprising a plurality of similar interlocking members, each comprising a tapered projection on one side and an aligned tapered recess on the opposite side for cooperation 40 with the complementary portions of similar members, the projection of each member being smaller than its recess, whereby each projection is adapted to have a clearance on 45 all sides thereof while interlocked.

5. The combination with a plurality of similar interlocking members arranged along the opposite sides of an opening and each provided with a tapered recess and 50 projection, of a slider for progressively controlling said members, the adjacent interlocking members being spaced apart longitudinally to permit of lateral flexibility and longitudinal movement without affecting the facility of engagement.

60. 6. A plurality of interlocking members adapted to be controlled by a slider, each member being provided with a projection on one side and a recess on the opposite side, the adjacent interlocking members being spaced apart when interlocked and the projections and recesses being tapered and proportioned to insure transverse flexibility of the fastener while interlocked.

7. A plurality of interlocking members 65 adapted to be actuated by a slider, each member being provided with a projection on one side and an aligned recess on the opposite side larger than said projection to permit clearance between the recess and the 70 projection of an adjacent member cooperating therewith, both the projection and recess having tapered sides forming an angle of about 33° with the vertical.

8. In a fastener, an interlocking member 75 having a transversely elongated recess on one side and an aligned transversely elongated tapered projection on the opposite side smaller than said recess in order to provide lateral clearance.

80. 9. The combination with a plurality of interlocking members arranged along the opposite edges of stringers, of a slider adapted to control said members, each member having a recessed portion on one side 85 and an aligned projection on the opposite side, both the recess and projection being tapered, the sides of the projection and the outer sides of the interlocking member on a transverse section through the recess and projection and normal to the stringers being at an angle to one another and with the outer sides of the interlocking member tapered less than the sides of the projection.

95. 10. The combination with a plurality of interlocking members arranged along the opposite edges of an opening, of a slider adapted to control said members, each member being provided with a transversely elongated and tapered recess and projection, one on one side and the other on the opposite side, said members being spaced apart longitudinally to permit shrinkage and stretching of the material to which they are applied, the spacing between said members being less than half the height of the projection on each member.

100. 11. In a fastener, a plurality of interlocking members arranged along flexible stringers on opposite sides of an opening 110 and adapted to be controlled by a slidable operating device, each member having a transversely elongated recess on one side and a transversely elongated projection tapered on the opposite side, the adjacent members on the same side of the openings being disconnected except for said stringers and spaced apart substantially more than the thickness of one member exclusive of its projection.

115. 12. An interlocking member adapted to be secured to a stringer and provided with a projection on one side and a recess on the opposite side for cooperation with similar members, the sides of said member and the sides of the projection taken on a transverse section through the recess and projection, at right angles to the plane of the stringer

being both inclined, with said sides of the projection being inclined a greater amount than the sides of the member.

13. An interlocking member adapted to be secured to a stringer and provided with a projection on one side and a recess on the opposite side for cooperation with similar members, the sides of said member and projection taken on a transverse section

angles to the plane of the stringer, being both inclined, with said sides of the projection forming an angle of about 33° with the vertical, while the sides of said member on the same transverse section form an angle ¹⁵ of substantially 12° with the vertical.

Signed at Meadville, in the county of Crawford and State of Pennsylvania, this 2nd day of January A. D. 1923.

GIDEON SUNDBACK.
